RAIL ANCHOR

Charles B. Shepherd, New York, N. Y., assignor to
The P & M Company, Chicago, Ill., a corpora-
tion of Illinois

Application February 3, 1928, Serial No. 251,571

3 Claims. (Cl. 238—330)

This invention relates to devices for preventing the longitudinal creeping of rails occasioned by the pumping and vibratory action of moving trains thereon, and more particularly to those devices known as rail anchors or anti-creepers.

This invention has for an object to provide a one-piece rail anchor having self-contained tension means, said tension means being positioned vertically to the bottom surface of the rail base and normally above the ballast line even with the cribs full and not subject to the loss of spring effect due to the pounding and stretching under the pumping motion set up by moving trains.

Another object of this invention is to provide a one-piece rail anchor processed from a flat piece of metal of relatively thin or narrow cross-section and so formed that the cross-sectional surfaces present edgewise contact with the rail and are the only surfaces which contact with the rail piece.

A further object of this invention is to provide a rail anchor having an intermediate curved body member, said body member having a lateral bend substantially at right angles to the main rail flange engaging means, an easy or sweeping bend, and a portion bent or turned upwardly to the other rail flange-engaging means on the opposite end of the device.

Further objects will become apparent from the following description, appended claims and the accompanying drawing which form a part of this specification, and in which

Figure 1 is a front view in elevation of a rail anchor device constructed in accordance with my invention shown applied to the base flange of a rail, the said base flange being shown in cross-section.

Figure 2 is a plan view of my rail anchor.

Figure 3 is an isometric view of the anchor illustrated in the preceding figures.

Figure 4 illustrates the relation of the anchor to the rail prior to application.

Figure 5 illustrates one of the positions assumed by the rail anchor during its application to the base flanges of the rail.

Referring to the drawing in which like reference numerals refer to like parts, the embodiment of my invention illustrated in Figures 1 to 5 is formed by blanking or stamping from a flat piece of metal of relatively thin or narrow cross-section, preferably carbon or alloy spring steel capable of being tempered.

The rail anchor as here illustrated comprises a jaw 1 adapted to engage the flange of the base

of the rail on one side thereof. The form or shape of said jaw may be of any contour, but preferably it is made to conform to the shape of the rail base flange which it is intended to grip and engage. It is also made of a slightly larger size for reasons hereinafter explained. Disposed on the opposite end of the device is an upstanding means 2 adapted to engage the opposite flange of the rail base when the anchor is in its applied position. This means may be of any suitable construction for engaging the vertical edge portion of the rail base to hold the jaw 1 from backing off the rail. In order to have little resistance to vertical tilting of the anchor when it is in use, the surfaces of the jaw portion which engage the top and bottom of the rail base are of a width corresponding to the thickness of the material from which it is formed. The jaw member 1 and the rail engaging means 2 are each provided with depending portions 6 and 7 designed to come in contact with some rigid portion of the track such as the cross-tie. These tie abutting portions may be made in the shape illustrated, or bent at any angle inwardly relative to the upright portions 1 and 2. Connecting the said jaw 1 and the said flange-engaging means there is a body member 3. This body member is provided with a lateral bend 4 adjacent the jaw 1 and substantially at right angles thereto. An easy or sweeping bend 4' provides a spring member exerting a strong pressure transversely on the rail flanges and also a shoulder 11 adapted to be struck by a spike maul or sledge or pressed on by a suitable tool during the application of the device to a rail. Succeeding this sweeping bend 4' the body member 3 is formed with a bend or turn 5 which inclines upwardly relative to the jaw 8' (Fig. 4). This bent portion 5 of the body member provides a vertical pressure against the bottom surface of the rail base at the surface 8 whereby the jaws 1 and 8' are caused to exert a strong lever grip on the base flange of the rail.

In order to facilitate tilting of the anchor and permit opposite edges of the rail engaging surfaces of the jaw members 1 and 8' to assume an angular position to the rail base and to bite the same with a wedge-like force, the clearance between the upper and lower jaw surfaces is slightly greater than the thickness of the rail base flanges which are engaged by said jaws.

In order to permit the upper and outer surface, or edge, of the laterally bent body portion 10 to come into angular contact with the bottom surface of the rail base and to function

as a brace to support the jaws in resisting any forward creeping of the rail, the top surface of said body portion is disposed in a plane lower than the rail engaging surfaces 8 and 8', and so 5 disposed that a tilting movement of the anchor about an axis extending transversely of the rail will force the upper edge of the body 5 into engagement with the bottom surface of the rail base approximately simultaneously with the contacting of said upper and lower jaw edges. 10

In applying my rail anchor to the rail, the jaw 1, since it is of a larger size than the rail flange, is partially slipped over the rail base flange until it does not go any further 15 and assumes the position illustrated in Figure 5. The shoulder 11 of the laterally bent portion 4' is then struck with a spike maul or sledge or pressed with a suitable tool whereby the rail engaging member 2 is caused to clear the edge 20 of the opposite flange and snap into place as shown in Figure 1. Due to the main jaw tie abutment 6 and the tie abutment 7 at the other end of the anchor, the anchor device is guided and supported during its application. Also these 25 abutments and the edgewise contact by the cross-sectional surfaces forming the contacting surfaces of the jaws 1 and 8' increase the tendency to tilt and thereby increase the biting or gripping action of the anchor device.

When applied in position on the rail base flange there will be a strong downward pressure where the upper rigid jaw member 1 is in contact with the top surface of the rail base flange and an upward pressure against the bottom surface of the opposite flange of the rail base at 8. Due to the resiliency of the easy bend 4' in the body member 3, the inner vertical surfaces of the rail engaging members 1 and 2 will exert a transverse pressure against the vertical edges of the rail base flanges.

I claim:

1. A sheet metal rail anchor for application edgewise on the base of a rail comprising a body extending under the rail base, a jaw member on one end of the body to extend around and engage said rail base at one side of the rail, a tie abutting element at the same end of the

body extending below said body, an upward extension on the other end of the body recessed to provide a small jaw arranged to automatically snap over and engage the upper corner portion of the rail base when the first mentioned jaw member is driven upon the other side of the rail base, and a tie abutting element at the small jaw end of the body extending below said body; said body being formed with lateral bends providing a bowed portion extending outwardly 10 away from the tie. 5

2. A sheet metal rail anchor for application edgewise on the base of a rail comprising a body extending under the rail base, a jaw member on one end of the body to extend around and engage said rail base at one side of the rail, a tie abutting element at the same end of the body extending below said body, an upward extension on the other end of the body recessed to provide a small jaw arranged to automatically snap over and engage the upper corner portion of the rail base when the first mentioned jaw member is driven upon the other side of the rail base, and a tie abutting element at the small jaw end of the body extending below said body; 15 said body being formed with lateral bends near the first mentioned jaw end of the body providing a short sharply bowed out portion and a longer portion extending diagonally of the rail base. 25

3. A sheet metal rail anchor for application edgewise on the base of a rail comprising a body extending under the rail base, a jaw member on one end of the body to extend around and engage the rail base at one side of the rail, an upward extension on the other end of the body formed with a jaw member arranged to automatically snap over and engage the top face of the rail base when the first mentioned jaw member is driven on the other side of the rail base, tie abutting members on both ends of the body extending below said body and continuous with said jaw members and upward extension respectively; said body being formed with lateral bends providing a bowed portion extending outwardly away from the tie. 35

CHARLES B. SHEPHERD.
